UNITED STATES PATENT OFFICE.

FREDERICK W. LORD, OF NEW YORK, N. Y., ASSIGNOR TO LORD MANUFACTURING COMPANY, OF NEW YORK, N. Y., A CORPORATION.

CORNER CLEAT.

1,402,304.

Specification of Letters Patent. Patented Jan. 3, 1922.

Application filed May 6, 1920. Serial No. 379,299.

To all whom it may concern:

Be it known that I, FREDERICK W. LORD, a citizen of the United States, and resident of the borough of Manhattan, city, county, 5 and State of New York, have invented certain new and useful Improvements in Corner Cleats, of which the following is a specification.

This invention relates to improvements in 10 corner cleats for securing together the corners of picture-frames and the like, and has for its principal object to provide a cleat adapted to be used principally in connection with mitred joints which, when driven into 15 place will cause the abutting edges of the mitre to firmly engage each other, so as to eliminate the necessity of using glue or a similar adhesive.

Another object of the invention resides in 20 the provision of a corner cleat which may be stamped from a single piece of material, thereby permitting the devices to be made in quantities at a reasonable cost.

A further object of the invention is to 25 provide a substantially L shaped cleat having points arranged in parallel rows which in turn are parallel to the mitre, so that when the device is driven into place the points act against the adjacent bars of the 30 frame to prevent their separation.

Still another object of the invention is to provide a device having the points of one leg inclined in a direction opposite those carried by the other leg, in such a manner 35 that when the device is driven into place the points will co-act in drawing the adjacent bars of the frame together.

With these and other objects in view, the invention consists of a novel construction, 40 combination and arrangement of parts which will be fully set forth in the following specification, claimed and illustrated in the accompanying drawings in which:—

Fig. 1, is a fragmentary view of a frame 45 showing this device in use.

Fig. 2, is a perspective view of the corner cleat and

Fig. 3, is a sectional view on line 3—3 of 50 Figure 1, showing the inclination of the points whereby the bars are drawn together.

Referring to the drawings in detail, the numeral 5 designates one bar of a frame, while the numeral 6 designates the adjacent bar of the frame. The abutting ends of each bar are mitred as illustrated in Figure 55 1, and the usual screening material 7 is secured in the frame in an ordinary manner.

The corner cleat is designated in its entirety by the numeral 8 and constitutes a substantially L shaped body having legs 9 60 and 10 arranged at right angles to each other, and provided with suitable openings or screw-receiving apertures 11 for the reception of attaching screws 12 which form an auxiliary securing means for the device. 65

Struck from the legs of the L shaped body are parallel rows or points and as shown in Figure 3 the points 13 of the leg 9 incline downwardly and outwardly away from the point where the legs join. The points 14 of 70 the leg 10 incline downwardly and outwardly in a direction opposite to the inclination of the points 13 and it will be noted upon reference to the drawings that the points are arranged in parallel rows with 75 their flat faces in planes parallel to the mitre.

In use the frame bars 5 and 6 are cut in the manner shown in Figure 1 and the corner cleat is then placed on the bars and it 80 will be seen that upon driving the cleat into place the points will act to draw the abutting ends of the bars into firm contact, thus making a tight joint. After the cleat has been driven into place the screws 12 are introduced through the openings 11 and driven home, and it will be seen that the frame will be firmly secured together. 85

While in the foregoing there has been shown and described the preferred embodiment of this invention, it is to be understood that certain minor changes in the details of construction, combination and arrangement of parts may be resorted to without departing from the spirit and scope of the invention as claimed. 95

What I claim is:—

The combination with a frame comprising frame bars mitred at their abutting ends, 100 of a one piece construction corner cleat com-

prising a substantially L shaped body and parallel rows of points struck from the body in planes parallel with the mitred ends of the frame bars, the points in one leg being 5 inclined downwardly and outwardly from the body and the points in the other leg

being inclined in the opposite direction whereby when the device is driven into place the frame bars will be drawn together.

Signed at New York city, this 23rd day 10 of April, 1920.

FREDERICK W. LORD.
